Patented Aug. 15, 1922.

UNITED STATES PATENT OFFICE.

WILLIAM C. LINEAWEAVER, OF FORT SILL, OKLAHOMA, ASSIGNOR OF ONE-HALF TO
WORTHINGTON SWIFT, OF LAWTON, OKLAHOMA.

COPY FASTENER.

1,425,873.

Specification of Letters Patent. Patented Aug. 15, 1922.

Application filed April 12, 1921. Serial No. 460,760.

To all whom it may concern:

Be it known that I, WILLIAM C. LINEAWEAVER, a citizen of United States, residing at Fort Sill, in the county of Comanche and State of Oklahoma, have invented certain new and useful Improvements in Copy Fasteners, of which the following is a specification, reference being had therein to the accompanying drawings.

10 This invention relates to copy holders and has for an object to provide a device of the class for use especially with copy which is to be secured to a board for photographing or copying in any other manner 15 and in which use a considerable number of the originals are placed preferably in the same location for the purpose of saving time in focusing the camera or arranging other details of the copying apparatus.

20 A further object of the invention is to provide a device having spaced penetrating points connected by an articulated bar so that one of said points may be permanently fixed in the board as a positioning 25 or registering member, while the other point hinged thereto may be moved about the inserted point as a pivot to secure the copy to the board in any approved manner.

30 A further object of the invention is to provide hinged members having perforations at or adjacent their ends, preferably similarly spaced upon opposite sides of the hinge and with penetrating members carried by the perforations with a screw-threaded head member attached to the screw member, not only for the purpose of attaching the pointed member to the bar but for manual engagement with the device in use.

40 A further object of the invention is to provide an articulated member having penetrating points equally spaced upon opposite sides of the articulating hinge with an engaging member clamping the penetrating 45 member to the articulated member so that the penetrating members may be replaced when damaged by use without discarding the entire instrument.

With this and other objects in view the 50 invention comprises certain novel parts, elements, units, mechanical movements, functions and combinations as disclosed in the drawing together with their equivalents

as will be hereinafter more fully described and claimed.

55

In the drawings:

Figure 1 is a perspective view of two of the devices in use retaining a picture upon a board in position to be photographed.

Figure 2 is a view of the device in side 60 elevation showing in dotted lines the pivoting of one of the sections from engaging to releasing position.

Figure 3 is a view partly in elevation and partly in section through one of the penetrating points and heads and taken on line 65 3, 3 of Figure 2.

Figure 4 is a perspective view of the units of the penetrating structure and head separated and removed from the articulated 70 bars.

Like characters of reference indicate corresponding parts throughout the several views.

75 In the securing of originals for the purpose of copying, either by photographic process or otherwise, especially where a considerable number of originals of like size and general uniform character are to be employed, it is desirable to have fixed members whereby the originals may always 80 register so that the copying apparatus, be it a camera or what it may, will require the minimum amount of adjustment for putting it in condition for copying.

85

90 The present invention embodies a pair of spaced points, one of which may be employed as a registering guide, while the other may be employed for penetrating the copy or penetrating only the supporting board to clamp the copy thereto. It comprises a pair of bars 10 and 11, similar each to the other, hinged together at 12. At the remote ends of the bars 10 and 11 perforations 13 are formed. A head member indicated at 14 is provided with a shank 15 proportioned to be inserted in and through the perforations 13 and an annular shoulder 16 to bear upon the bars 10 and 11 respectively. The shank 15 is hollow and 100 screw-threaded as at 17 to receive the screw-threaded lug 18. The lug 18 is preferably integral with an annular shoulder member 19 which clamps upon the side of the bars 10 and 11 by inserting the shank 15 in the 105 opening 17 and clamping the shoulders 16

and 19 upon opposite sides of the bars by screwing together the two members as indicated more particularly at Figure 3. A penetrating point 20 is formed as an organized structure together with the shoulder 19 so that either of the penetrating points may enter the board 21 whereupon is positioned the original as at 22.

As shown at Figure 2 one of the penetrating points 20 will be employed as the positioning member permitting the other one to swing upon the hinge 12 to the dotted line position shown therein for the purpose of releasing the original. Preferably also, when the original is properly registered upon the point remaining inserted in the board, the other point will be inserted through the original itself into the board. In case it is desired not to perforate the original, both points may be inserted in the board outside the margin of the original as shown at Figure 1. While at Figure 1 two of the devices are shown as securing the original to the board, it is obvious that any greater number may be employed as circumstances may make desirable. With a plurality greater than two of the devices, the proper registering and positioning of the original will be made more convenient and certain whether the second penetrating member enters through the original or only at the margin as shown.

It is obvious that by retaining one of the penetrating points in position upon the board, the succeeding original may be spaced to correspond identically with the preceding original and then clamped by the second penetrating point, the first being sufficiently loose to permit the original to be slipped under the bar at that end.

If preferred, the device may be applied to the corner of the frame as indicated in dotted lines, Figure 1.

What I claim to be new is:

1. A copy holder comprising a pair of bars hinged together and provided upon opposite ends of the hinge with spaced perforations, penetrating points secured in the perforations, and means carried by the bars and the perforations for manual control of the device.

2. A copy holder comprising a pair of articulated bars having corresponding spaced perforations upon opposite ends of the pivoting; penetrating points carried by the bars

inserted in the perforations and extending upon the same side of the articulated bars, and manual engaging means carried upon the opposite sides of the bars and opposite to and for controlling the penetrating points. 60

3. A copy holder comprising articulated bars, penetrating points carried removably by the bars equally spaced upon opposite sides of the articulation, and manual engaging heads carried upon the opposite sides 65 of the bar adjacent to and for controlling the penetrating points.

4. A copy holder comprising bar sections hinged together, penetrating points carried by the bar sections adjacent their remote 70 ends and extending upon the same side of the combined hinged structure, and manual engaging heads carried by the bar sections opposite to and for controlling the penetrating points. 75

5. A copy holder comprising bar sections pivoted intermediate their ends, penetrating points carried removably by the bars at their remote ends and equally spaced upon opposite ends of the hinging, and removable 80 manual engaging heads carried by the bar sections upon the sides opposite to and for controlling the penetrating points.

6. A copy holder comprising articulated bar sections having perforations adjacent 85 their remote ends, penetrating points having shanks inserted through the perforations, and manual engaging heads having means for engaging with the shanks and clamping the penetrating points upon and 90 to the bar sections.

7. A copy holder comprising articulated bar sections having perforations at their opposite ends equally spaced upon opposite ends of the articulation, manual engaging 95 heads having shanks proportioned to be inserted through and substantially fill said perforation and having internally screw-threaded bore, and penetrating points provided with screw-threaded shanks proportioned to be inserted in the screw-threaded 100 bore and with the manual engaging member to be clamped by the actuation of said screw-threaded engagement upon the bar sections.

In testimony whereof I hereunto affix my 105 signature in presence of two witnesses.

WILLIAM C. LINEAWEAVER.
